UNITED STATES PATENT OFFICE.

ANTONY SCHORNO, OF PASSAIC, NEW JERSEY.

METALLIC ENVELOP-SEAL.

No. 857,908.

Specification of Letters Patent.

Patented June 25, 1907.

Application filed November 6, 1906, Serial No. 342,260.

To all whom it may concern:

Be it known that I, ANTONY SCHORNO, a citizen of the Republic of Switzerland, residing at Passaic, in the county of Passaic, State 5 of New Jersey, United States of America, have invented certain new and useful Improvements in Metallic Envelop-Seals; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part of 15 this specification.

My invention relates to metallic letter seals and has for its object to produce a simple seal made from a single piece of metal suitably bent to form and capable of fastening an 20 envelop or the like to prevent unauthorized opening, as will hereinafter be more particularly described and claimed.

Referring to the drawings in which like parts are similarly designated, Figure 1, 25 shows an extended flat metal blank having a tubular eyelet formed thereon. Fig. 2, is a longitudinal section through the blank with some of its parts bent in proper position. Fig. 3, shows the blank Fig. 2, bent to form 30 and ready for use. Fig. 4, shows the seal after being forced into locking position. Fig. 5, shows the alternate tongues 6 bent downward. Fig. 6, is a section showing a modification.

The seal consists preferably but not necessarily of a single piece of sheet metal such as is usually used for such purposes as soft brass or soft iron as the maker may elect to use and consists of a main long narrow strip 1 having 35 a disk 2 at one end and a locking ring 3 at the other end, which ring is connected by a short strip 4 to an eyelet or tube 5 whose head is surrounded by a number of sharp ended or triangular tongues 6 one of which forms a 40 unit with or is replaced by the short strip 4. The disk 2 is connected by a short strip 7 to a retaining ring 8 having a number of supporting projections 9 preferably having blunt 45 ends. The blank described is then struck up 50 to form by a suitable die or dies, the tube 5 having a circular depression or downwardly projecting bead 10 formed on the under side of the head and the alternate pointed tongues 6 bent down and preferably, but not necessarily, 55 bent slightly inward. The ring 3 is

struck up to conical form and the disk 2 has formed on it an embossment at its center to form an eyelet-upsetting device or anvil 11 while the ring 8 has its blunt ended tongues 9 bent upward as shown in Fig. 2. The blank 60 so prepared is bent to form shown in Fig. 3 short strip 7 being bent at its center so that the bent blanks 9 of the ring 8 will surround the anvil 11, and the anvil 11 will lie below the center of the ring. The long strip 1, then 65 is bent so that the ring 3 will register with the retaining ring 8 and anvil 11, and the short strip 4 is then reversely bent so that the eyelet will come over the anvil as shown in Fig. 3.

In order to seal an envelop the anvil is 70 slipped inside the envelop below the flap the back of the envelop coming between the anvil and locking ring 3, the flap is then slid under the eyelet as shown in Fig. 3. To effect sealing only necessitates the striking 75 of the eyelet head with any suitable instrument, the eyelet cuts through the flap, passes through the locking ring 3, the back of the envelop, the retaining ring 8 onto the anvil and cuts out two small disks from the two 80 layers of paper. The anvil causes the spreading or upsetting of the under end of the eyelet; at the same time the pointed bent tongues 6 pass through the envelop flap and engage the conical walls of rings 3 and are bent upward under the flap. The lower end of the eyelet beneath the flap and on the anvil being upset, expands under retaining ring 8 and the conical locking ring 3 is mashed flat the bent tongues 6 lying on top of it, substantially as shown in Fig. 4. It will be seen that 90 it is practically impossible to withdraw the eyelet from the retaining ring 8, as the locking ring 3 immediately above 8 prevents the metallic strip from being unfolded. 95

In Fig. 6 I have shown a seal having three instead of four folds or bends having dispensed with the ring 8, the anvil being surrounded by an equivalent means such as the bent over edge 12 of the anvil disk 2^a and 100 have also dispensed with the bent down tongues 6 around the eyelet head.

I claim:

1. A letter seal comprising a metal strip having an eyelet at one end and an anvil at 105 the other end, and a locking ring between them, said metal strip being bent to aline the anvil, locking ring and eyelet.

2. A letter seal comprising a metal strip having an eyelet at one end, an anvil at the 110

other end and a locking ring between them, said metal strip being bent to aline the anvil, locking ring and eyelet and retaining means adjacent the anvil to engage the end of the eyelet when upset on the anvil.

3. A letter seal comprising a metal strip having an eyelet at one end, an anvil at the other end, and a locking ring between them and means above the anvil to engage the end of the eyelet when upset all formed of a single piece of metal.

4. A letter seal comprising a metal strip, an eyelet at one end, tongues on the head of the eyelet extending generally in the direction thereof, an anvil on the other end of the strip, a conical locking ring between them and engaging means proximate the eyelet to engage the end thereof when upset.

5. A letter seal comprising a metal strip having an eyelet at one end, an anvil at the other end a locking ring between them and a retaining ring connected to the anvil and bent to bring the parts into vertical alinement.

25 6. A letter seal comprising a metal strip having an eyelet at one end, an anvil at the other end, a locking ring between the ends and a retaining ring having supporting projections thereon, substantially as described.

30 7. A letter seal comprising a metal strip having at one end an eyelet whose head has a number of downward projecting pointed tongues, an anvil at the other end of the strip, a conical locking ring between the eyelet and

35 anvil, and a retaining ring connected to the anvil and having a number of supporting

projections substantially at right angles to the plane of the ring.

8. A letter seal comprising a metal strip having a headed eyelet at one end, a bead on the under side of the head, an anvil at the other end of the strip and a locking ring between the ends, said strip being bent to substantially axially aline the anvil, locking ring and eyelet.

45 9. A letter seal comprising a metal strip having at one end an eyelet whose head has a number of downward projecting pointed tongues, and a bead on the under side of the head, an anvil at the other end of the strip, and a retaining ring connected to the anvil and having a number of supporting projections substantially at right angles to the plane of the ring.

50 10. A letter seal formed of a single piece of metal and comprising a strip having an eyelet formed at one end having a serrated head, the alternate tongues of which are bent down, an anvil punched up from the other end, a locking ring between the anvil and eyelet and connected to both, and a retaining member connected to the anvil and bent over the same, said eyelet arranged to pass through the locking and retaining rings to be upset by the anvil.

55 In testimony that I claim the foregoing as my invention, I have signed my name in presence of two subscribing witnesses.

ANTONY SCHORNO.
